UNITED STATES PATENT OFFICE.

FREDERICK RATCLIFF, OF NEW BEDFORD, MASSACHUSETTS, ASSIGNOR TO
THE PAIRPOINT MANUFACTURING COMPANY, OF SAME PLACE.

DESIGN FOR A COFFIN-PLATE.

SPECIFICATION forming part of Design No. 22,507, dated June 6, 1893.

Application filed January 18, 1893. Serial No. 458,859. Term of patent 7 years.

To all whom it may concern:

Be it known that I, FREDERICK RATCLIFF, a citizen of the United States, residing at New Bedford, in the county of Bristol and State of Massachusetts, have invented and produced a new and original Design for Coffin or other Plates, of which the following is a specification, reference being had to the accompanying drawing, showing my design.

• A is the plate, and B its border, wrinkled at b to indicate drapery and crossed at inter-

vals by ridges b' to indicate bands by which the drapery is tied back from the plate.

What I claim is—

The design for a coffin or other plate herein described, substantially as shown in the accompanying drawing.

FREDERICK RATCLIFF.
